WILLIAM P. WHITLEY, OF ST. LOUIS, MISSOURI, ASSIGNOR TO RAWLINGS MANUFACTURING COMPANY, OF ST. LOUIS, MISSOURI, A CORPORATION OF MISSOURI

SHOULDER AND CHEST PROTECTING DEVICE

Application filed May 2, 1928. Serial No. 274,549.

This invention relates to shoulder and chest protecting devices of the kind that are used by football players, and particularly to protecting devices of the type that comprise two connected pads or main sections that extend over the shoulders, shoulder blades and upper portion of the chest of the user.

The main object of my present invention is to provide a shoulder and chest protecting device of the general type mentioned in which the means that is used to hold the two pads or main sections of the device in operative position on the user's body is inexpensive to construct, is capable of being adjusted quickly and easily either to draw the two main sections into snug engagement with the user's body, or to release said sections, and is of such design that it will securely hold said main sections in adjusted position, notwithstanding the fact that the holding means is held or retained by frictional pressure.

Figure 1 is a perspective view of a shoulder and chest protecting device embodying my present invention.

Figure 2 is a detail view, showing one of the side straps, the tunnel or channel that receives the doubled portion of said strap, and the loop, ring or guide in the tunnel through which said strap passes; and

Figure 3 is a horizontal sectional view, taken on the line 3—3 of Figure 2, looking in the direction indicated by the arrows.

Referring to the drawings which illustrates the preferred form of my invention, A designates two pads or main sections that extend over the shoulders and preferably downwardly over the shoulder blades and upper portion of the user's chest, the opposed adjacent inner edges of said main sections A being connected together in any preferred or suitable manner, as, for example, by a lacing 1 arranged at the front side of said sections, and a similar lacing (not shown) arranged at the rear side of said sections.

The sections or pads A are held in snug engagement with the user's body by two retaining members B, preferably side straps that extend under the user's arms, and which are combined with the sections A in such a way that it is only necessary to exert a pull

on the free ends of the side straps B in order to draw the sections A into snug engagement with the user's body. Each of the holding members or side straps B is permanently connected at one end, preferably at its rear end, to the rear side of one of the sections A, and the opposite end of said strap is adjustably connected to the front portion of the section A of the device with which said strap co-operates.

The novelty of my improved shoulder and chest protecting device consists in the means that is used to adjustably connect the side straps or holding members B to the sections A of the device. Each of the sections A is provided at its front side, adjacent its bottom edge, with an internal tunnel or channel that extends inwardly from the side edge of said section, and which is open at its outer end. A loop, eye or other suitable device 2 is arranged inside of said tunnel some distance inwardly from the outer end of the tunnel so as to form a guide around which or through which the side strap or holding member B passes, as shown in broken lines in Figure 1. Any suitable means can be used to anchor the loop or eye 2, but I prefer to use a strip of material 3, which, after being passed through the eye 2, is doubled and the terminal portions of said strip then secured to the front portion of the pad A preferably by the stitches 4 that are used to close the inner end of the tunnel or channel in which the doubled portion of the side strap B is positioned.

The frictional engagement between the doubled portion of each of the side straps B and the walls of the tunnel in which said doubled portion is positioned is made use of to hold said side strap in adjusted position, and in order to eliminate the possibility of said strap slipping, I prefer to arrange a partition 5 in the tunnel that extends inwardly some distance from the outer end of the tunnel and which is interposed between the two overlapping parts of the doubled portion of the side strap B that is positioned in said tunnel, thus, in effect, forming a separate casing or passageway for each part of the doubled portion of the side strap that comprises two side walls that embrace said

part. The side straps B can be formed from webbing or any other suitable material, and the portions of the main sections or pads A that constitute the tunnels for the double portions of the side straps can be constructed from any suitable material that has a tendency to prevent said side straps from slipping. I prefer, however, to construct the partitions 5 of said tunnels from leather and 10 also provide the side walls of said tunnels with leather facing pieces that extend either over the entire area of said side walls, or over a portion of the area of said side walls. In the form of my invention herein illustrated the front wall of each tunnel is provided with an inner facing 6 of leather that extends throughout the entire length of said wall, and the rear wall is provided with an inner facing 7 of leather that extends inwardly some distance from the end of the tunnel, as shown in Figure 3.

Each of the side straps B extends forwardly from the rear side of the particular section A of the device with which said strap 25 co-operates, thence inwardly through the tunnel in the front portion of said section to the loop or ring 2 arranged adjacent the inner end of said tunnel, the strap then extending in the opposite direction to the outer 30 end of the tunnel, as shown in Figure 3. Due to the fact that each part of the double portion of the strap is arranged between the partition 5 and the opposed side wall of the tunnel, there is sufficient frictional area between 35 the strap and the parts of the structure that engage the doubled portions of the strap to eliminate the possibility of the strap slipping accidentally. To tighten the side straps B so as to draw the sections or pads A into 40 snug engagement with the user's body, it is only necessary to exert an outward pull on the free ends of the side straps B, and to loosen the device or release it from snug engagement with the user's body, it is only 45 necessary to pull outwardly on the portions of the side straps B that extend under the user's arms. Accordingly, a shoulder and chest protecting device of the construction above described has the desirable characteristic of being capable of being drawn into 50 snug engagement with the user's body simply by pulling the side straps in one direction, and is capable of being released simply by pulling said straps in the opposite direction. 55 After being adjusted, however, there is little danger of the side straps or holding members B slipping accidentally, due to the relatively great frictional area between the doubled portions of said straps and the side walls of 60 the two casings in which the overlapped parts of the doubled portions of said straps are positioned. A holding means of the construction above described is sufficiently strong and rugged to successfully withstand 65 the strains to which shoulder and chest pro-

tecting devices are subjected when in use, and it is inexpensive to manufacture.

Having thus described my invention, what I claim as new and desire to secure by Letters Patent is:

1. A shoulder and chest protecting device, comprising two connected pads or main sections, side straps arranged under the user's arms and having their rear ends connected to the rear portions of said sections, a tunnel in the front portion of each of said sections that extends inwardly from the side edge of said section, a device arranged in each of said tunnels and permanently anchored in same, for receiving a doubled portion of the side strap that is positioned in the tunnel, and a vertically-disposed immovable partition in each of said tunnels that divides the interior of the tunnel into two separate and distinct passageways, each of which comprises side walls that exert frictional pressure on one part of the doubled portion of the side strap.

2. A shoulder and chest protecting device, comprising two connected pads or main sections, side straps having their rear ends attached to the rear side of said sections, tunnels in the front portion of said sections that extend inwardly over the side edges of said sections, an eye or loop in each tunnel, adapted to receive a doubled portion of the side strap that is positioned in the tunnel, a holding device for each of said eyes formed from a strip of material that is doubled and then secured by stitches to the section in which the tunnel is formed, and means in each of said tunnels that exerts frictional pressure on the two overlapped parts of each strap.
